ELEVATOR FOR INVALIDS

George P. Scott, Kansas City, Mo., assignor to
 Electro Lift Chair Corporation, Kansas City,
 Mo., a corporation of Missouri

Application September 16, 1948, Serial No. 49,467

12 Claims. (Cl. 187—14)

1

This invention relates to an elevator for carrying invalids, elderly and incapacitated persons up and down stairs and has for its principal object to provide a device of this character that is of simple and inexpensive construction and which is readily installed on conventional stairways.

Other objects of the invention are to provide a track and a car movable thereon by means of a cable; to provide a safe and positive brake mechanism for stopping movement of the carriage in case of failure of the cable or lessening of the tension thereon; to provide for electrical operation of the carriage in a manner which eliminates trolley wires and other exposed electrical connections; to provide a structure whereby movement of the carriage is under control of the occupant seated thereon; and to provide a carriage in the form of a seat to facilitate mounting by the individual or incapacitated person.

In accomplishing these and other objects of the invention I have provided improved structure, the preferred form of which is illustrated in the accompanying drawings wherein:

Fig. 1 is a sectional view of a portion of a stairway equipped with an elevator constructed in accordance with the present invention, a portion of the track and side of the carriage being broken away to better illustrate the construction.

Fig. 2 is a front elevational view of the carriage with a part of the front wall broken away to illustrate the motor winding drum and speed reduction gearing.

Fig. 3 is a positive view of the track and carriage particularly illustrating the limit switches and their actuating cams.

Fig. 4 is a positive view showing adjustment of the carriage relatively to the angle of inclination of the track so as to position the seat substantially horizontal.

Fig. 5 is a fragmentary positive view, particularly illustrating the brake mechanism.

Fig. 6 is a similar view showing the brake mechanism seat responsive to failure of the control cable.

Fig. 7 is a wiring diagram of the electrical circuits.

Referring more in detail to the drawings:

1 designates a stairway comprising a series of steps composed of conventional treads and risers 2 and 3 and whereon a person may climb from a lower floor to an upper landing 4. In the illustrated instance the steps are closed at the ends by a stringer 5. Supported on the nosings 6 of the respective treads adjacent the stringer 5 is a track 7 comprising spaced rails 8 and 9. The

5 rails preferably comprise channel-shaped members having vertically arranged webs 11 and upper and lower flanges 12 and 13 facing inwardly as shown in Fig. 3. The rails are of sufficient length to extend from the lower floor to a point above the seat level and are interconnected at intervals along their length by cross ties 10 attached to the lower flanges 12 of the respective rails. The upper ends of the rails are connected by a housing 14 which encloses a spring actuated reel 15 adapted to wind and unwind an electrical conductor cable 16 that supplies current to the actuating motor as later described. The rail 8 preferably has the web thereof secured to the stringer 5 by fastening devices such as screws 17 (Fig. 1) whereby the track is maintained in stable position and at one side of the stairs so that the opposite side may be used in conventional manner.

20 Movable mounted on the track and adapted to move the length thereof is a carriage 18 which includes a platform-like seat 19 that is carried on substantially horizontal rails 20. The seat supporting rails 20 have relatively short downwardly projecting legs 21 and 22 at their rear ends and substantially longer vertical legs 23 and 24 at their forward ends. The shorter legs 21 and 22 carry a transverse axle 25 that extends between the track rails and which is provided on the ends thereof with rollers 26 and 27 adapted to roll on the lower flanges of the rails and retained thereon by the upper flanges as best shown in Fig. 5. Connected with the vertical legs 23 and 24 are leg extensions 28 and 29 which are 25 preferably formed of angles and have their flanges fitting within the angle formed by the flanges of the upper legs, the flanges of the legs being provided with slots 30 and 31 to pass fastening devices such as screws 32 and 33 whereby the 30 leg extensions may be adjusted to maintain the seat 19 in substantially horizontal position when the rails are applied to stairs of different inclination.

45 The sides of the carriage are closed by substantially triangular-shaped plates 34 and 35 and the front is closed by a plate 36 which extends from the seat to the bottom of the legs 23 and 24. The plates thus cooperate with the legs and frame of the seat to provide a rigid structure 50 and to form an enclosure for mounting the motor 37, reduction gearing 38 and winding drum 39 as later described. The lower ends of the leg extensions are connected by an angle 40 which has rollers 41 and 42 mounted on the ends thereof to operate between the flanges of the rails in the

same manner as the rollers 26 and 27. Fixed to and extending between the front and rear legs is a base plate 43 having a downset portion 44 to which the motor 31 is secured by suitable fastening devices, such as bolts 45. The base plate also includes an upper portion 46 on which the speed reduction gear unit 38 is similarly attached by bolts 48 (Fig. 1), the armature shaft of the motor being connected with the driving shaft of the reduction gearing by a flexible coupling 49. The outer end of the drum shaft is preferably supported by a bearing block 39' that is attached to the base plate 43.

The power delivery shaft 50 of the reduction gearing projects laterally and mounts the winding drum 39 as shown in Fig. 2. Fixed to the upper end of the track, for example, to a cross member of the housing 14 is the end of a cable 51 that is of sufficient length to extend along to the lower end of the track and connect with the winding drum 39, the connection preferably being made by extending the end of the cable through a side flange 52 of the winding drum and securing it onto the outer side thereof by a clamping washer 53 attached by a fastening device 54 as best shown in Fig. 2.

An operating current is supplied to the motor 31 through the flexible cable 16 that is connected with the reel 15. The reel 15 is simply to take up the conductor as the carriage moves up the stairs and may be of any conventional construction. The cable contains conductors 55 and 55' which connect with a controller switch 56 that in turn is connected with the terminals 57, 58 and 59 of the reversible motor through conductors 60, 61 and 62.

In order to limit movement of the carriage at the upper and lower limits of the track, the rail 10 is provided with cams 63 and 64 that project into the path of rollers 65 and 66 carried on crank arms 67 and 68 of switches 69 and 70. The switches 69 and 70 may be mounted on the inner side plate of the carriage as shown in Fig. 3 so that the rollers 65 and 66 are in position to engage the respective cams 63 and 64. The switches 69 and 70 are respectively connected in circuit with the conductors 60 and 62 so as to open circuit to the motor when the carriage reaches the upper and lower ends of the track as later described.

With the structure thus far described, it is obvious that failure of the lifting cable or reel drive might be a hazard and to avoid a possibility that would result in too rapid a descent of the carriage, the carriage is provided with a brake mechanism which comprises a transverse shaft 72 journaled in suitable bearings 73 and 74 that are mounted on the front legs 21 and 22 as shown in Fig. 5. Fixed to the ends of the shaft 72 are eccentric wheels or cams 75 and 76 having roughened or knurled peripheries 77 adapted to frictionally engage the upper flanges of the track rails when the shaft is moved in a clockwise direction to effect gripping of the rails and stop descent of the carriage. The brake wheels or cams are ordinarily retained out of engagement with the flanges of the track rails by an arm 78 that is carried on a sleeve 79 that is fixed to the shaft 72 by suitable fastening devices such as set-screws 80. The arm 78 carries a grooved wheel 82 that bears upon the cable 51 responsive to action of a spring 83. The spring 83 has one end suitably attached to the front of the carriage housing and the rear end is connected with the flexible cable 84 that extends around the front 75 Patent is:

axle and connects with the arm 71 as indicated at 85 (Figs. 1 and 5). It is thus obvious that when the cable is intact and in taut condition the wheel 82 will hold the brake cams out of engagement with the rail flanges against action of the spring, however, in case of failure or breakage of the cable, the spring 83 will become effective to cause rotation of the transverse shaft 72 and movement of the peripheries of the braking cams 75 and 76 into clamping contact with the flanges of the track rails, thereby preventing accidental descent of the carriage.

The front of the carriage may be provided with a foot rest 86 for supporting the feet of the passenger when the passenger is mounted on the seat.

In installing an elevator mechanism constructed as described, the track 7, including the channel-shaped rails 8 and 9, is positioned at one side of the stairway preferably so that the rails bear upon the nose 6 of the respective treads 2 as shown in Fig. 1, after which the rail 8 is secured to the adjacent stair stringer by the fastening devices 17. The carriage, after being mounted on the track, is adjusted so that the leg extensions 28 and 29 are in position to support the seat 19 substantially horizontally as shown in Fig. 1. After adjustment the screws 32 and 33 are tightened. The switch cams 63 and 64 are then applied in proper position on the web 11 of the track rail 9 so as to limit upward and downward movement of the carriage at the ends of the track.

Assuming that the carriage is at the lower end of the track, the cable 51 is substantially unwound from the winding drum 39 and the electrical cable 16 is withdrawn from the spring reel. A person desiring to be elevated to the upper level 4 mounts the seat 19 and moves the controller switch 56 to a position for rotating the motor in the direction to effect lift of the carriage. When the motor 31 is energized, the winding drum 51 will be operated to wind up the cable thereon and draw the carriage upwardly of the track. When the carriage reaches the upper end 45 of the track, the roller 65 of the switch 69 engages the cam 63 so as to open circuit to the motor and stop movement of the carriage. The carriage will remain in position at the upper end of the track because the low ratio of the speed reduction gear automatically locks and prevents unwinding of the cable.

When it is desired to descend the stairs, the control lever is operated in the opposite direction to reversely energize the motor to rotate the winding drum in an opposite direction to pay out the cable and allow descent of the carriage. When the carriage reaches the lower end of the track the roller 66 engages the cam 64 to open the switch 70, whereupon downward movement of the carriage is stopped.

When the cable is intact, the brake elements 75 and 76 are retained out of braking position, however, in case the cable 51 should break the spring 83 is immediately effective to draw the brake elements into engagement with the rails of the track to prevent descent of the carriage.

From the foregoing it is obvious that I have provided an elevator for invalids and other incapacitated persons which is readily mounted on a stairway and which is of simple and inexpensive construction, safe in operation and which is conveniently and safely operated.

What I claim and desire to secure by Letters

1. An elevator comprising a self contained unit including a track adapted for support on the treads of a stairway, a carriage movable along the track, a winding drum on the carriage, a cable having one end anchored to the upper end of the track and adapted to wind on said drum to lift the carriage and to unwind from the drum for lowering the carriage on the track, a reversible motor on the carriage, a speed reduction mechanism on the carriage and connecting the motor with the winding drum, means for supplying current to the motor, and a controller on the carriage for controlling the current supply.

2. An elevator comprising a self contained unit including a track adapted for support on the treads of a stairway, a carriage movable along a track, a winding drum on the carriage, a cable having one end anchored to the upper end of the track and adapted to wind on said drum to lift the carriage and to unwind from the drum for lowering the carriage on the track, a reversible motor on the carriage, a speed reduction mechanism on the carriage and connecting the motor with the winding drum, means for supplying current to the motor, a controller on the carriage for controlling the current supply, and brake means on the carriage contacted with the cable and adapted to engage the track upon failure of the cable.

3. An apparatus of the character described including a track adapted for support on a stairway, a carriage movable along a track, a winding drum on the carriage, a cable having one end anchored to the upper end of the track and adapted to wind on said drum to lift the carriage and to unwind from the drum for lowering the carriage on the track, a reversible motor on the carriage, a speed reduction mechanism connecting the motor with the winding drum, means for supplying current to the motor, a controller on the carriage for controlling the current supply, limit switches on the carriage, and means on the respective ends of the track for operating the limit switches to limit the extent of movement of the carriage on the track.

4. An apparatus of the character described including a track adapted for support on a stairway, a carriage movable along a track, a winding drum on the carriage, a cable having one end anchored to the upper end of the track and adapted to wind on said drum to lift the carriage and to unwind the drum for lowering the carriage on the track, a reversible motor on the carriage, a speed reduction mechanism connecting the motor with the winding drum, means for supplying current to the motor, a controller on the carriage for controlling the current supply, brake means on the carriage connected with the cable and adapted to engage the track upon failure of the cable, limit switches on the carriage, and means on the respective ends of the track for operating the limit switches to limit the extent of movement of the carriage on the track.

5. An apparatus of the character described including an inclined track, a carriage, means supporting the carriage for movement on the track, a winding drum on the carriage, a reversible motor on the carriage, speed reduction mechanism connecting the motor with the winding drum, a cable connected with the upper end of the track and adapted to be wound on the winding drum, a brake shaft extending transversely of the carriage, braking means on the ends of the brake shaft engageable with the track, a

crank arm connected with the brake shaft and having means engaging the cable to support the braking means out of contact with the rails, and a spring connected with said arm and the frame to set the brake means incidental to slack in said cable.

6. An apparatus of the character described including an inclined track, a carriage operable on the track, a winding drum on the carriage, a cable fixed with respect to the track and adapted to be wound on the winding drum, a brake shaft extending transversely of the carriage, braking wheels eccentrically mounted on the ends of the brake shaft and engageable with the track, a crank arm connected with the brake shaft, a wheel on said arm and engaging the cable to support the braking wheels out of contact with the rails and a spring for retaining said wheel on the crank arm in contact with the cable and adapted to rotate the brake shaft incidental to failure of the cable to set the braking wheels against the track to stop descent of the carriage.

7. An apparatus of the character described including a track means adapted for support on a stairway, a carriage means movable along a track, a winding drum having fixed support on one of said means, a cable having one end anchored to the other of said means and adapted to wind on said drum to lift the carriage and to unwind the drum for lowering the carriage on the track, a reversible motor connected with the winding drum, a flexible insulated cable for supplying current to the motor means carried by the track for winding up and paying out of the insulated cable upon up and down movement of the carriage means including means for connecting the cable with a source of current, a controller on the carriage means and connected with the insulated cable and motor for controlling the current supply to the motor, and brake means on the carriage means normally engaging the first named cable and adapted to engage the track upon failure of the cable.

8. An elevator comprising a self-contained unit including a track adapted for support on the treads of a stairway, a carriage movable along the track, a reversible motor on the carriage, a speed reduction mechanism on the carriage and connected with the motor, a driving connection between the speed reduction mechanism and the track, a controller on the carriage, an electrical supply circuit connected with the controller and motor, and limit switches on said unit and connected with said circuit for automatically stopping the carriage at the respective ends of the track, each of said limit switches having an operating part and a trip part with one of said parts of the respective switches being on the carriage and the other parts being respectively at the upper and the lower end of the track and in position to be engaged by the parts on the carriage when the carriage reaches the respective ends of the track.

9. An elevator comprising a self-contained unit including a track adapted for support on the treads of a stairway, a carriage movable along the track, a winding drum on the carriage, a cable connecting the carriage with the upper end of the track and adapted to wind on said drum to lift the carriage and to unwind from the drum for lowering the carriage on the track, a reversible motor on the carriage, a speed reduction mechanism on the carriage and connecting the motor with the winding drum, a controller on the carriage, an electrical supply circuit con-

nected with the controller and motor, and limit switches on said unit and connected with said circuit for automatically stopping the carriage at the respective ends of the track, each of said limit switches having an operating part and a trip part with one of said parts of the respective switches being on the carriage and the other parts being respectively at the upper and the lower end of the track and in position to be engaged by the parts on the carriage when the carriage reaches the respective ends of the track.

10. Elevator mechanism embodying therein an inclined runway including laterally spaced rails, a carriage having members for guided travel longitudinally of said rails, drum means journaled on said carriage, means on the carriage for driving the drum means in either direction, cable means operatively attached at one end to the upper end of the inclined runway, and at its other end operatively disposed upon said drum means for a winding upon or an unwinding therefrom to take up or to pay out said cable means.

11. Elevator mechanism embodying therein an inclined runway including laterally spaced rails, a carriage having members for guided travel longitudinally of said rails, drum means journaled on said carriage, a reversible motor on the carriage for driving the drum means in either direction, cable means operatively attached at one end to the upper end of the inclined runway, 30 and at its other end operatively disposed upon

said drum means for a winding upon or an unwinding therefrom to take up or to pay out said cable means, means for starting the motor and for causing it to run in either direction.

12. Elevator mechanism embodying therein an inclined runway including laterally spaced rails, a carriage having members for guided travel longitudinally of said rails, drum means journaled on said carriage, a reversible motor on the carriage for driving the drum means in either direction, cable means operatively attached at one end to the upper end of the inclined runway, and at its other end operatively disposed upon said drum means for a winding upon or an unwinding therefrom to take up or to pay out said cable means, means for starting the motor and for causing it to run in either direction, and means operative as the carriage reaches the end of its travel in either direction on the runway for automatically stopping the motor.
